UNITED STATES PATENT OFFICE.

GEORGE A. BURNHAM, OF SAUGUS, MASSACHUSETTS, ASSIGNOR TO SEARS E. CONDIT, JR., OF BROOKLINE, MASSACHUSETTS.

TIME-LIMIT RELAY.

1,140,249.

Specification of Letters Patent. Patented May 18, 1915.

Application filed February 5, 1913. Serial No. 746,282.

To all whom it may concern:

Be it known that I, GEORGE A. BURNHAM, a citizen of the United States, residing at Saugus, in the county of Essex and State of Massachusetts, have invented an Improvement in Time-Limit Relays, of which the following is a specification.

This invention relates to time-limit relays and is intended as an improvement on the time-limit relay shown in Letters Patent #1,041,716, dated October 15, 1912.

The invention has for its object certain improvements in the means for operating the switch-controller or switch at the end of a predetermined period of time, which is simple, not liable to become injured when its co-operative parts are moved suddenly into engagement with each other, not liable to get out of order and which is adapted for a wide range of adjustment, and in all positions of adjustment the operating device is moved against the full force of its return spring.

Figure 1 is a side elevation of a time-limit relay embodying this invention. Fig. 2 is a plan view of the switch-controller and operating device therefor. Fig. 3 is a front view of the parts shown in Fig. 2.

The controller for the switch, as here shown, consists of a circuit-closer for the circuit of a tripping-coil, yet in lieu thereof any form of switch-controller may be employed. Said circuit-closer comprises a pair of stationarily supported circuit-closing members 12, 13, and a movable circuit closing member 14, adapted to engage said stationary members. Said movable circuit-closing member is here represented as an upright pin arranged on a rotatable friction-disk 15, at a place quite well removed from the axis and said disk is arranged in a horizontal plane and has on its under side a central vertical spindle 16, which has its bearing in an arm 17. Said friction-disk is arranged beneath a friction-wheel 20, secured to a horizontally arranged rotatable shaft 21, and is movable into and out of engagement with the periphery of said wheel, but is normally held in retracted position or out of engagement with said wheel, as represented in Fig. 1. When moved into engagement with said wheel it is driven rotatably by said wheel to move the pin 14, orbitally into engagement with the circuit-closing members 12, 13. The speed of rota-

tion of the friction-disk is in accordance with or proportionate to the diameter of the wheel and the distance said wheel is located with respect to the axis of the disk, and its speed may be varied by shifting the position of the wheel 20 on its shaft, thereby to vary its position with respect to the axis of the disk, which may be accomplished by securing said wheel to its shaft in an adjustable manner, as for instance, by a set-screw 18. A very wide range of adjustment may be obtained by thus adjusting the position of the wheel 20. The shaft 21 may be calibrated to determine the position of the wheel, and thus the speed of rotation of the friction-disk.

In the patent aforesaid engagement of the operating device with its actuator and also rotary movement of the actuator is controlled by means responsive to an overload, and, as here shown, an electric-motor of the rotary type, similar to that shown in the aforesaid patent, is employed which is constructed and arranged to move the friction-disk into engagement with the friction-wheel and permit of disengagement therefrom, and also to rotate the friction-wheel, thereby to operate the switch-controller. But in lieu of this means for accomplishing this result other means may be employed which admits of engagement of the disk and wheel upon the occurrence of an overload and of disengagement thereof upon cessation of the overload, and which positively rotates the friction-wheel, thereby to drive the disk. As here shown, the shaft 21 to which the friction-wheel is adjustably secured is represented as an extension of the shaft of the armature 48 of the motor, and the field-frame of the motor is divided horizontally or otherwise, 50 representing the upper part and 51 the lower part thereof, and said parts are hingedly connected together at 52, so that the lower part is movable toward and from the upper part which latter is held stationary. Movement of said lower part of the field frame in a direction away from the upper part is limited by any suitable means, and movement toward the upper part is controlled by any suitable means, so far as the present invention is concerned, although, as here shown, said frame has an ear 53, with yielding stops associated with it, see Fig. 1. The arm 17 bearing the friction-disk is pivotally connected to the lower 110

part of the field-frame and is supported in a yielding manner by a spring 19, so that when said lower part is moved suddenly by the attractive force of the magnet field the 5 said friction-disk is moved suddenly into engagement with the friction-wheel and the parts will not be injured. A return-spring 25 is provided for the friction-disk which is connected at one end to the disk and at the 10 other end to the arm, and said spring acts when permitted to move the disk backward until a pin 26 on the disk strikes a pin 27 on the arm, thus limiting its backward movement, and determining its normal position 15 and also the normal position of the circuit-closing member 14.

In the present construction the friction-disk always returns to its normal position or starting point, which position is not adjustable or variable, so that when moved 20 rotarilby by the friction-wheel it is always moved against the full force of the return-spring regardless of the speed incident to the relative dispositions of the disk and 25 wheel.

In operation, upon the occurrence of an overload the lower part of the field-frame of the motor will be attracted and the friction-disk will be moved into engagement with 30 the friction-wheel, and the shaft of the motor will be rotated thereby rotating the friction-wheel and thus rotating the friction-disk which, at such time is in engagement with it, thus to cause the pin 14 to 35 engage the circuit-closing members 12, 13, and upon cessation of the overload said friction-disk will be permitted to immediately retract thus disengaging the friction-wheel, and also said friction-disk will 40 be restored immediately to normal position by its return-spring.

My present invention is not limited to all the structural details here shown, as it is obvious they may be changed without deviating from the spirit and scope of the 45 invention.

I claim:—

1. In a time-limit relay, a friction-wheel, means responsive to an overload to rotate 50 said wheel, a rotatable friction-disk arranged with its axis at right angles to the axis of said wheel and movable into and out of engagement with the periphery of said wheel, and when in engagement therewith to be rotated by it, and a controller for the switch operated by said friction-disk, substantially as described.

2. In a time-limit relay, a rotatable friction-wheel, a rotatable friction-disk arranged with its axis at right angles to the axis of said wheel and movable into and out of engagement with the periphery of said wheel and when in engagement therewith to be rotated by it, means responsive to an overload to move said disk into engagement with

said wheel, permitting disengagement upon cessation of the overload, and a controller for the switch operated by said disk, substantially as described.

3. In a time-limit relay, a rotatable friction-wheel and a rotatable friction-disk arranged with its axis at right angles to the axis of said wheel and movable into and out of engagement with the periphery of said wheel and when in engagement therewith to be driven by it, means responsive to an overload to move said disk into engagement with said wheel and also to rotate said wheel, and a controller for the switch operated by said friction-disk, substantially as described. 70 75

4. In a time-limit relay, a rotatable friction-wheel, a rotatable friction-disk arranged with its axis at right angles to the axis of said wheel and movable into and out of engagement with the periphery of said wheel and when in engagement therewith to be rotated by it, means responsive to an overload to move said disk into engagement with said wheel, permitting disengagement therefrom upon cessation of the overload, a 90 spring to return said disk to normal position when disengaged from the wheel, and a controller for the switch operated by said disk, substantially as described. 85

5. In a time-limit relay, a rotatable friction-wheel, a rotatable friction-disk arranged with its axis at right angles to the axis of said wheel and movable into and out of engagement with the periphery of said wheel and when in engagement therewith to be rotated by it, a yielding arm bearing said disk, means responsive to an overload and connected with said arm to move said disk into engagement with said wheel, permitting disengagement therefrom upon cessation of the overload, and a controller for the switch operated by said disk, substantially as described. 95 100

6. In a time-limit relay, a rotatable friction-wheel, a rotatable friction-disk arranged with its axis at right angles to the axis of said wheel and movable into and out of engagement with the periphery of said wheel, and when in engagement therewith to be rotated by it, means responsive to an overload to move said disk into engagement with said wheel, means to disengage said disk from said wheel upon cessation of the overload, and means to impart retrograde motion to said disk when disengaged from the wheel to return it to normal position, and a controller for the switch operated by said disk, substantially as described. 110 115 120

7. In a time-limit relay, an electric-motor responsive to an overload, a friction-wheel 125 adjustably secured to the shaft of said motor, a rotatable friction-disk arranged with its axis at right angles to the axis of said wheel and movable into and out of engagement with the periphery of said wheel and when

in engagement therewith to be rotated by it, and a controller for the switch operated by said friction-disk, substantially as described.

8. In a time-limit relay, an electric-motor responsive to an overload, a friction-wheel arranged on the shaft of said motor, a rotatable friction-disk arranged with its axis at right angles to the axis of said wheel and to be rotated by said wheel when in engagement therewith, and movable means supporting said friction-disk arranged in the magnetic field of the motor, whereby said disk is movable into and out of engagement with said wheel respectively upon occurrence and cessation of the overload, and a switch-controlling member operated by said disk, substantially as described.

9. In a time-limit relay, an electric-motor responsive to an overload, having a part of its field-frame made movable, a friction-wheel secured to the shaft of the motor, a rotatable friction-disk borne by said movable portion of the wheel frame arranged with its axis at right angles to the axis of the friction wheel, said disk being movable into and out of engagement with said wheel respectively upon the occurrence and cessation of an overload, and rotated by said wheel while in engagement therewith, and a switch-controller operated by said disk, substantially as described.

10. In a time-limit relay, an electric-motor responsive to an overload having a part of its field-frame made movable, a friction-wheel secured to the shaft of the motor, a rotatable friction-disk borne by said movable portion of the wheel frame arranged with its axis at right angles to the axis of the friction wheel, said disk being movable into and out of engagement with said wheel respectively upon the occurrence and cessation of an overload, and rotated by said wheel while in engagement therewith, and a switch-controller operated by said disk, substantially as described.

motor, a rotatable friction-disk yieldingly connected with said movable portion of the field-frame and arranged with its axis at right angles to the axis of the friction-wheel, said disk being movable into and out of engagement with said wheel respectively upon the occurrence and cessation of an overload, and rotated by said wheel while in engagement therewith, and a switch-controller operated by said disk, substantially as described.

11. In a time-limit relay, an electric-motor responsive to an overload having a part of its field-frame made movable, a friction-wheel secured to the motor shaft, a rotatable friction-disk arranged with its axis at right angles to the axis of the wheel, an arm bearing said disk which is pivotally connected to and yieldingly supported by said movable part of the field-frame, whereby said disk is movable into and out of engagement with said wheel respectively upon the occurrence and cessation of an overload, and is rotated by said wheel while in engagement therewith, and a switch-controller operated by said disk, substantially as described.

In testimony whereof, I have signed my name to this specification, in the presence of two subscribing witnesses.

GEORGE A. BURNHAM.
